GAS RECIRCULATION METHOD AND APPARATUS FOR SUPERHEAT CONTROL WITH GAS FAN STATIC CONTROL

George E. Moonan, Crestwood, N.Y., assignor to The Babcock & Wilcox Company, New York, N.Y., a corporation of New Jersey

Filed Oct. 26, 1955, Ser. No. 542,927

4 Claims. (Cl. 122—479)

This invention relates to apparatus for, and a method of, generating and superheating high pressure steam, wherein the temperature of the superheated steam is maintained at a predetermined value by gas recirculation.

The invention is exemplified in a steam generating and superheating unit involving a furnace, the walls of which include steam generating tubes in which at least a predominant portion of the total generated steam is generated as a result of radiant heat transmission from the furnace gases, the furnace being provided with high temperature gases by a coal burning means operating at temperatures above the fusion temperature of the combustible in the coal. The heating gases pass from the furnace over a convection superheater, and a recirculated gas system withdraws lower temperature gases from a position in the gas stream beyond the superheater and introduces the gases into the furnace in increasing volume percentage-wise as the steam generating rate decreases. In the operation of such a unit, fused or semifused particles of slag, from the fuel, may accumulate upon the screen tubes and different sections of the convection heating means such as the superheater, and such accumulations may increase to such an extent that the draft loss through the furnace is materially increased. Under such circumstances the total draft resistance may be built up to such an extent that it exceeds the maximum static ability of the gas recirculating fan. When this occurs, the fan may be ruined within a few minutes because of the reverse flow of gases through the fan. Additionally, there is apt to be a sudden increase in draft loss under conditions wherein the steam load suddenly changes from, for example, 50 percent load to 100 percent load when, at the same time, the amount of recirculated gas flow called for by the control system of the unit, approaches zero as the steam load approaches 100 percent load. The draft loss varies as the square of the change in load, and under these circumstances that would mean that the draft loss is increased four times. This situation is apt to cause a reversal of flow of the recirculated gas through the fan and likewise increase the liability of ruining the fan in the manner above indicated. This invention involves a method of, and means for, preventing the above indicated type of damage to the fan without increasing the size of the fan or increasing the power requirements for operating the fan. According to the invention, when the recirculated gas flow to the furnace decreases to such an extent that the fan outlet static pressure approaches, to a predetermined degree, the gas pressure within the furnace, gas is bled from the fan exit and recirculated to the fan inlet, this flow of bled gases being controlled in such a manner that the minimum amount of gas handled by the fan wheel does not drop below that required for the maximum static pressure peak of the fan. According to the invention all of the gas would be recirculated around the wheel of the fan at maximum boiler load when the flow of recirculated gases into the furnace is zero, and no bled gas would be recirculated around the fan wheel at boiler loads requiring recirculated gas flow

2

in excess of that delivered at fan static peak. The flow of bled gases recirculating about the fan wheel may, within the scope of the invention, be controlled manually or automatically.

5 The invention also involves the recirculation of gas about the fan wheel from the fan exit to the fan inlet in such a manner that the amount of gas so bled and recirculated about the fan wheel is greater than that required at maximum fan static peak, to attain an upward characteristic of fan static at maximum boiler loads.

10 The invention also involves means and a method of effecting the above indicated results, involving simultaneously, both the controlled inlet of cold air to the inlet of the recirculating gas fan, and the bleeding of gas from 15 the outlet of the recirculating gas fan to its inlet at low rates of flow of recirculated gas, in order to maintain the fan static at, or near, its peak.

15 The invention involves an increase in the flow of cold air from the forced draft fan of the unit into the inlet

20 side of the recirculated gas fan, and an increase of the flow of bled gases from the outlet of the recirculating gas fan to its inlet as the flow rate of recirculated gas into the furnace decreases beyond a predetermined value (which may take place simultaneously with increase in

25 air flow), and also provides means for protecting the fan by insulating the fan from gas or air connection with the furnace when the pressure differential between the fan outlet and the furnace falls below a predetermined amount, for example 1½" of water. In the practice of 30 the invention pressure connections are added to the fan outlet and the furnace inlet to measure the pressure differential between the duct between the fan outlet and the furnace inlet, which is restricted in such a manner that the predetermined resistance is achieved. As the 35 pressure differential remains well above 1½" of water, the flow of recirculated gases to the furnace is controlled or modulated from such variables as steam temperature and rate of vapor generation. As the pressure differential decreases and approaches 1½" of water, a damper

40 may be automatically opened (simultaneously with the increased gas recirculation around the fan rotor) to permit cold air from the forced draft fan to enter the recirculating fan inlet. The amount of this opening is adjusted as required to allow sufficient cold air to enter and lower the total temperature of the recirculating gas, thus 45 maintaining a 1½" pressure differential between the recirculating fan outlet and the furnace inlet. The automatic system preferably operates so that, if the differential pressure continues to fall, which would be a sign that the furnace resistance is increasing, and the cold air damper reaches its wide open position so that no further margin may be gained, then the system operates to render the fan motor inoperative. At the same time inlet and 50 outlet dampers on the inlet and outlet sides of the fan are closed and cold air dampers upstream and downstream of the inlet and outlet dampers are opened so that the fan is completely surrounded with cold air. A second 55 precaution involved in the automatic control system involves a temperature switch at the recirculating fan outlet. If the temperature rises in this outlet, which would indicate a reversal of flow of hot gases toward the fan, the motor is automatically stopped and the fan is automatically insulated as previously described. In addition to these features of the automatic system an 60 alarm is also provided in this circuit which warns the operator that the furnace resistance is dangerously high when the pressure differential approaches 1½" of water.

65 The invention will be concisely set forth in the claims, but for a complete understanding of the invention, its uses and advantages, recourse should be had to the following description which refers to a preferred embodiment illustrated in the accompanying drawings.

Of the drawings:

Fig. 1 is a diagrammatic representation of a gas recirculation system embodying the invention and associated with a vapor generating and superheating unit; and

Fig. 2 is a vertical sectional view of the vapor generating and superheating unit with which the gas recirculation system of Fig. 1 is associated.

In Fig. 1 there is diagrammatically illustrated a cyclone furnace 20 burning a slag forming fuel and discharging high temperature furnace gases into a primary furnace chamber 22, from the lower part of which the gases flow upwardly as indicated at 24 into a vertically elongated secondary furnace chamber 25, the walls of which include steam generating tubes. This secondary furnace chamber, the succeeding convection section including the steam superheater, and the pertinent recirculated gas system for control of superheated steam temperature over a wide range of rate of vapor generation, are constructed and arranged in the manner shown and described in the pending patent application Serial No. 278,872, filed on March 27, 1952, by P. H. Koch, now Patent No. 2,884,909, and belonging to the same assignee. As disclosed in said application and illustrated in Fig. 2, the products of combustion pass upwardly through the secondary furnace chamber 25 and over a secondary superheater 27 to a downflow convection gas pass 29, then successively contact a primary superheater 31 and an economizer 33, and then flow into a duct 35 leading to an airheater 37. In communication with the duct 35 is the inlet of a duct 28 of a heating gas recirculation system.

In the illustrative steam generating and superheating unit of Fig. 2 the elements of the superheater 27 are arranged as pendent superheater platens disposed within a vertically elongated secondary furnace chamber receiving the combustion products from the cyclone furnace, the latter being an example of fuel burning means. Parts of the dependent superheater platens are disposed in a part of the secondary furnace chamber 25 receiving combustion products including high temperature heating gases with particles of fused slag suspended therein. In the illustrative unit there is a recirculated gas system including a fan and duct work having its inlet downstream in a gas-flow sense from the superheater, and having its gas outlet in communication with the upper part of the primary furnace chamber 22. This gas recirculation system and its associated controls operate to maintain the temperature of the superheated steam at a predetermined value over a wide load range, and to accomplish this, the flow of recirculated gas to the primary furnace chamber, is increased as the steam load decreases, in a lower part of the load range. The recirculated gas system also functions to decrease the ratio of furnace absorbed heat to the total heat absorbed in superheating the vapor, as the steam demand decreases, this action also involving an increase in a proportion of the total heat absorbed by the superheater.

Referring further to the system shown in Fig. 1 as being a part of such a unit as that shown in the above identified pending patent application, the recirculated gas system includes a recirculating gas fan 26, preferably operated by an appropriate electric motor and receiving partially cooled heating gases through a duct 28, the inlet of which is in communication with the gas flow of the unit at a position beyond the superheater. The outlet of the fan 26 is connected by the duct work component 30 and 32 to an outlet 34 communicating with the primary furnace chamber 22.

As the rate of steam demand decreases toward a low load value, and as the rate of firing of the cyclone furnace 20 is decreased, the dampers 36, disposed in the duct work component 30 are open and controlled or modulated to increase the recirculated gas flow through the opening 34 into the primary furnace chamber 22. The dampers 36 may be operated throughout a wide load

range by appropriate control mechanism including a damper operator 38 appropriately connected to the dampers 36 by linkage 40. The damper operator 38 is intended to respond to changes in pneumatic loading pressure in the control line 42 and the connected control line 44, leading from a controller 46 in which, or connected with which, there are suitable and known control devices for varying the loading pressure in the lines 42 and 44 in response to the conjoint influences of a plurality of variables such as load or rate of vapor generation, and superheated steam temperature.

The controls above referred to may be considered as the normal operative controls for maintaining final steam temperature substantially at a predetermined value and, in practice, these controls may be such as those shown and described in the pending application to Paul S. Dickey, Serial No. 260,357 and filed on December 7, 1951, or in the pending patent application of Charles S. Smith, Serial No. 199,406, now abandoned, filed on December 6, 1950, or appropriate gas recirculation control components such as those indicated in the patent application of Durham and Weaver, Serial No. 322,646, filed on November 26, 1952. All of these applications are assigned to The Babcock & Wilcox Company and/or its wholly owned subsidiary, The Bailey Meter Company.

In general, the pertinent normal operative controls of the flow of recirculated gas operate to increase the flow of recirculated gas as the vapor generating load decreases toward a predetermined low load, with a minimum flow of recirculated gas at a relatively high load value.

The type of unit with which the pertinent controls of recirculated gas flow are associated is one in which the fuel burning means such as the cyclone furnace 20 operates under a positive, or super-atmospheric pressure created by such means as the forced draft fan 50, the outlet of which includes duct work 100 having air flow control dampers 101 and duct work 52 leading to the air inlet of an air heater from which the air flows by appropriate duct work to the air inlet of the fuel burning means 20. Thus there normally is a relatively high gas pressure at the position of the recirculated gas outlet 34 into the primary furnace chamber 22, which gas pressure must be overcome by the operation of the recirculated gas fan 26 in order for the recirculated gas to flow from the fan into the primary furnace chamber. In practice, it has been determined that there must be a pressure differential resulting from flow between the position H, or the outlet 34 of the recirculated gas system into the primary furnace chamber, and the position I adjacent the outlet of the fan 26 of a value greater than $1\frac{1}{2}$ " of water, and to effectively utilize the actual pressure differential between these points as a means to indicate a low rate of flow the pressure differential controller F, or 54 has opposite sides of its diaphragm connected by the lines 56 and 58 to the outlet side of the fan 26, and to the upper part of the primary furnace chamber, respectively, at positions I and H, respectively. This pertinent pressure differential may be decreased by an increase in draft loss through the furnace occasioned by abnormal slagging of the screen and various convection sections, and by a sudden increase in the rate of vapor generation. When due to such conditions, the pressure differential at F is decreased below the predetermined value, there is apt to be a reverse flow of the high temperature heating gases from the upper part of the primary furnace chamber 22 and through the duct components 32 and 30, and through the fan 26. Such a reverse flow of gases would ruin the fan within a matter of minutes to cause great economic loss not only to operators of the electric generating station with which the steam generating unit is associated but also to the users of the power developed thereby. Such a contingency is prevented by the present invention.

As disclosed in the copending applications of H. G.

Stallkamp, Serial No. 542,926, filed October 26, 1955, now Patent No. 2,875,736, and L. G. Troutman, Serial No. 542,925, filed October 26, 1955, when the differential pressure between the points I and H, measured by the differential pressure controller 54, approaches or drops below 1½" of water, which means that the recirculated gas flow is approaching a dangerous condition, the associated controls so change the pneumatic loading pressure in the line components 60—62 that the alarm M is sounded and, simultaneously as a result of the signaling of the relay J through the change in loading pressure in said line components, opens the damper A''' through the agency of the damper operator A', sufficiently to permit such flow of the gases from the duct opening 64 in the outlet of the fan 26 and through the communicating ducts 65 to and through the duct 66 and the opening 68 in the duct 28 or in the inlet box of the fan 26 that the pressure differential between H and I is restored to a value well above 1½" of water. Simultaneously with the opening of the damper A, the damper D may be opened by the action of the damper operator D' in response to the same loading influence in the line components 60—62, as continued through the line component 70, the damper D being likewise closed after the pressure differential between the points H and I has been restored to a value well above 1½".

If the differential pressure between the positions H and I continues to fall and drops below 1½" of water while the damper A''' is wide open then the pressure switch K picks up the influence or impulse through the lines 60 and 74 from the relay J; and through the lines 72 and 74, turns off the fan motor switch 76; closes the dampers E through the intermediary of the damper operator 38 and its connections; closes the dampers C and opens the dampers B through the agency of the loading line 80, the control components 82 and 84, the line 86, the damper operator 88 and its connections 89—92; to insulate the fan 26 and permit the relatively high pressure cold air from the outlet of the forced draft fan 50 to flow through the duct components 100, 102 and 32 directly into the primary furnace chamber through the opening 34.

As an additional safety factor, if other controls fail, the temperature switch L, having the element 110 responsive to gas temperatures within the opening 34 or the upper part of the primary furnace chamber, operates, upon a dangerous rise in temperature, through the agency of the loading line 112 to stop the fan motor, close dampers C and E and open the dampers B through their connections which are illustrated.

The dampers which are shown in the drawing are preferably arranged so that they may be alternatively, manually or automatically operated through the use of selector switches indicated in one of the above identified pending applications, and thus, for the insulation of the recirculating gas fan other than that above referred to the operator may manually open the damper D and the dampers B to permit cold air to flow to the primary furnace and to the inlet side of the fan, and to close the dampers A, C and E, thus providing for bodies of cold air on both inlet and outlet sides of the fan, after the fan motor is stopped.

Although the invention has been described with reference to a preferred embodiment thereof, it is to be appreciated that the invention is not necessarily limited to all of the details of that embodiment. The invention is, rather, to be taken as of a scope commensurate with the scope of the subjoined claims.

What is claimed is:

1. In a vapor generating and superheating unit, wall means including vapor generating tubes normally receiving heat predominantly by radiant heat transfer from high temperature furnace gases within a furnace chamber formed by the wall means, fuel burning means in the form of a cyclone furnace supplying the furnace chamber with high temperature heating gases, a forced draft

fan and associated ductwork normally supplying the cyclone furnace with super-atmospheric combustion supporting air, means forming a gas pass leading from the furnace chamber, a convection superheater including tubes internally receiving the steam generated in said generating tubes and subject externally to the flow of said heating gases after loss of heat therefrom in the vapor generating zone, a recirculated gas system including a fan and fan inlet ductwork communicating with the heating gas flow in the gas pass downstream of the superheater and having fan outlet ductwork communicating with the furnace chamber, dampered by-pass or shunt ductwork having its inlet connected with the gas space on the outlet side of the recirculating gas fan and having its outlet connecting with the gas space on the inlet side of the fan, and a damper in said shunt ductwork to permit recirculation of the gases around the rotor of the recirculated gas fan to maintain a predetermined gas pressure differential between the furnace and the gas fan outlet.

2. In a high pressure steam generating and steam superheating unit, means defining a furnace, steam generating means including steam generating tubes along the walls of the furnace, fuel burning means for firing the furnace including a combustion air supply system having an air supply fan, a steam superheater for superheating the steam generated in said tubes, the superheater being subject to the heat from the heating gases generated in the furnace, a gas recirculation system including a gas recirculating fan and fan inlet ductwork communicating with the heating gas flow downstream of the superheater in a gas flow sense, the gas recirculation system also having fan outlet ductwork leading to a position in the furnace upstream of the superheater in a gas flow sense, and means including shunt ductwork having an inlet communicating with recirculated gas flow on the outlet side of the recirculated gas fan, the shunt ductwork also having an outlet communicating with the inlet side of the recirculated gas fan and providing for the recirculation back through the fan of a proportion of the gases flowing through the gas recirculation system to maintain a predetermined gas pressure differential between the furnace and the gas fan outlet.

3. In a high pressure elastic fluid generating and superheating unit, means defining a furnace, steam generating means including elastic fluid generating tubes along the walls of the furnace, fuel burning means for firing the furnace including a combustion air supply system having an air supply fan, a superheater for superheating the elastic fluid generated in said tubes, the superheater being subject to the heat from the heating gases generated in the furnace, a gas recirculation system including a gas recirculating fan and fan inlet ductwork communicating with the heating gas flow downstream of the superheater in a gas flow sense, the gas recirculation system also having fan outlet ductwork leading to a position in the furnace upstream of the superheater in a gas flow sense, and means including shunt ductwork having an inlet communicating with recirculated gas flow on the outlet side of the recirculated gas fan, the shunt ductwork also having an outlet communicating with the inlet side of the recirculated gas fan and providing for the recirculation back through the fan of a proportion of the gases flowing through the gas recirculation system to maintain a predetermined gas pressure differential between the furnace and the gas fan outlet.

4. In a vapor generating and superheating unit, walls including vapor generating tubes defining a furnace having a heating gas outlet in one of said walls, means for supplying heating gases to said furnace, walls forming a gas pass opening at one end to said gas outlet, a vapor superheating tube bank in said gas pass in the path of gas flow leaving said furnace and connected for series flow of fluid from said vapor generating tubes, gas recirculation means for maintaining a predetermined vapor

temperature as the vapor generating load changes including a gas fan, gas fan inlet ductwork communicating with said gas pass downstream gas-wise of said tube bank for withdrawing heating gases, and gas fan outlet ductwork communicating with said furnace for discharging the withdrawn gases thereto, and means for increasing the flow of gases through the gas fan to increase the static pressure thereof, while maintaining the rate of flow of recirculated gases into said furnace substantially constant, said last named means including a dampered duct opening at one end to the gas fan inlet ductwork and at its other end to the gas fan outlet ductwork.
